UNITED STATES PATENT OFFICE.

PAUL CARPENTIER, OF ZURICH, SWITZERLAND.

LAP-BACK FOR BOOKBINDING.

No. 861,261.

Specification of Letters Patent.

Patented July 30, 1907.

Application filed December 14, 1906. Serial No. 347,838.

To all whom it may concern:

Be it known that I, PAUL CARPENTIER, a citizen of the Republic of Switzerland, residing at Zurich, Switzerland, have invented certain new and useful 5 Improvements in Lap-Backs for Bookbinding; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to a sheet for book-binding, for the purpose of forming a lap-back. As is well known, a lap-back differs from an ordinary back, inasmuch as 15 the various sections of the book, in the case of the former, are attached to double laps, instead of being secured as ordinarily, direct to the bands.

The invention is illustrated in the accompanying drawing, in which 20 Figure 1, is an elevation of the sheet, Fig. 2, a cross section through a portion of the same drawn to a larger scale. Figs. 3 and 4 are perspective views and Fig. 5 is a sectional view, illustrating the application of the sheet in binding.

25 As shown in Figs. 1 and 2, the binding sheet comprises a plurality of parallel sections 1 having lateral end connections 3, 4, forming a gap 2 between the adjacent sections. The sheet is pasted to a flexible backing 5, of any suitable material such as linen or canvas. 30 Each section 1 has a central slit 6 which divides it into two halves 1^a and 1^b and in each half, adjacent to the slit is formed a recess 8^a and 8^b respectively. After securing the binding sheet to the backing 5, the connections 3 and 4 may be cut off and the sections 1 and backing. 35 5 trimmed to the size of the sheets 9 to be bound. The trimmed sheet is now folded at the gaps 2, and at the slits 6, in a zig-zag manner so as to form a double lap as shown in Fig. 3. The sheets 9 to be bound are secured to the flexible backing 5 at the gaps 2. Securing 40 members such as loops 7, which may consist of metal staples or a flexible material are mounted in the backing 5 at the slits 6 and are preferably located in such manner that the loop in one slit is displaced relatively to the loop of the adjacent slit, as shown in Fig.

4, but they may be disposed in any other or preferred manner. Strips 10 which serve as bands are drawn through the loops and owing to the provision of the recesses 8^a and 8^b the loops 7 do not cause the back to bulge. These recesses have the further advantage of rendering the lap-back particularly pliable since they 50 admit of the individual laps being bent independently of each other and a book may be readily opened at any place in the same uniform manner as shown in Fig. 5. This is especially the case when several recesses are provided at each side. 55

I claim:

1. A sheet for lap-back binders comprising a plurality of parallel sections each having a central longitudinal slit 60 formed therein and a recess formed on each side of the latter.
2. A sheet for making a lap-back for book-binding, comprising a plurality of stout parallel sections connected at the ends so that they form a single sheet, each section being slit centrally and recessed at each side of the slit.
3. A lap-back binder comprising a flexible member, and 65 a plurality of parallel sections secured to said member each having a central longitudinal slit and a recess on each side of the latter.

4. A lap-back binder comprising a flexible member, a plurality of longitudinally slotted sections mounted thereon to form a gap between the adjacent sections whereby the flexible member may be folded to lay the sections together, and securing members located in the slits and projecting beyond the edges of the sections when they are folded. 70

5. A lap-back binder comprising a flexible member, a plurality of longitudinally slotted sections each having a recess formed therein on each side of the slit and secured to the flexible members to form a gap between the adjacent sections, loops mounted in the flexible member projecting 80 through the slits, and bands threaded through the loops.

6. In combination, in a sheet for making a lap-back for book-binding, a plurality of stout parallel sections, connected at the ends so that they form a single sheet, each slit centrally to form a hinge and recessed at each side of the slit, and means located in the slits adapted to attach binding-bands. 85

In testimony that I claim the foregoing as my invention, I have signed my name in presence of two subscribing witnesses.

PAUL CARPENTIER.
